UNITED STATES PATENT OFFICE.

JOHN CLIFFORD MILLER, OF CINCINNATI, OHIO.

DESIGN FOR A CLASS PIN OR EMBLEM.

57,704.

Specification for Design. Patented Apr. 26, 1921.

Application filed June 8, 1920. Serial No. 387,466. Term of patent 14 years.

To all whom it may concern:

Be it known that I, JOHN CLIFFORD MILLER, a citizen of the United States, residing at Cincinnati, in the county of Hamilton and State of Ohio, have invented a new, original, and ornamental Design for a Class Pin or Emblem, of which the following is a specification, reference being had to the accompanying drawing, forming part thereof.

Figure 1 is a face view of the pin or emblem embodying my new design.

Fig. 2 is a side elevation thereof.

The essential features of my design consist in the general outline of the body of the pin or emblem, having on its face side the representation of a building, with an at-

tenuated tower in the foreground, beacon ray lines emanating or radiating from the central dome of the building, and a panel space at the base of the tower. The words "Veritas Vincit" are arranged at the end of the ray lines and at the opposite sides of the tower.

Having thus described my invention, I claim:

The ornamental design for a class pin or emblem, as shown and described.

JOHN CLIFFORD MILLER.
